LANDING GEAR

Frederic R. Harris, New York, N. Y., assignor to
Stanolind Oil and Gas Co., Tulsa, Okla., a cor-
poration of Delaware

Application August 26, 1948, Serial No. 46,309

9 Claims. (Cl. 14—71)

1

This invention is an improved landing gear comprising members adapted to set up a passageway between a fixed pier and a floating ship or vessel moored thereto.

An important object is to provide landing gear supported so that it can swing through an arc of substantially 180 degrees; and comprising a stairway member adjustably connected at one end to the outer end of a gangway member, and at its opposite end kept within stepping distance of the deck of the vessel that is held in position by its own power and a mooring line made fast to the pier; combined with a counterweight which at all times acts to brace and steady the passageway that links the vessel and the pier together.

My main purpose is to provide landing gear which can always be operated to swing out within reach of the vessel and secured to its deck; although the vessel approaches from different directions; and which will always efficiently serve its purpose, even in rough weather.

The invention is illustrated in the drawings which present one form only of the improvement; and I reserve the right to make changes in details without deviating from the general plan or underlying principle thereof.

Figure 1 is a plan view showing the general arrangement of an embodiment of my improved landing gear and indicating the mode of adjustment and operation, the boom which is normally directly above and supporting the gangway member being shown in dotted outline at various positions in its orbit.

Figure 2 is a side view thereof.

Figure 3 shows the connection between the stair member and the gangway member of the landing gear; partly in cross section; and

Figure 4 is a front view of said connection.

The landing gear works to advantage by installing it on a pier, dock or wharf having a deck 1 and a flight of steps 2 leading down each face of the pier at a corner thereof to a curved platform 3 supported on the corner of the pier at a suitable distance below the deck 1. The landing gear, indicated at 4, is designed to connect the platform 3 to the deck of a ship 5; and comprises a stair member 6 joined to a gangway member 7, which in turn is pivotally united to and suspended from a fabricated boom 8; extending outward from the corner of the deck 1. The boom 8, which in operation is actually directly over the gangway member, is for clarity omitted and shown in dotted lines displaced from its normal position and in duplicate to indicate its swinging range. This boom can be swung about

5 through an arc of 180 degrees or more, as indicated in Figure 1. It carries the stair member 6 and gangway member with it as it moves; and it can be turned and made to lower the landing gear upon the vessel 5, by hand or by any suitable arrangement of transmission devices connected to a source of mechanical power. The gangway member 7 is supported with its inner end approximately flush with the round platform 3; and when it is in place with the stair member 6 on the deck of the ship 5, the crew and others can easily leave the ship or return to it.

10 The boom 8 is composed of steel beams in open-work pattern, and the top and bottom plan thereof have substantially the outline of a shuttle, with straight converging sides at each end. The converging beams at the two extremities on the top are shown at 9, and they are connected by parallel side beams 10 at the middle of the boom. Along the lower part of the boom the converging beams at the ends are indicated at 19 (Figure 2), these beams being joined at their inner ends to the beams 20 along the middle, the beams 20 at the two sides being parallel to each other like the beams 10 above them. The upper and under faces of the boom can be further strengthened by cross beams 11 and diagonal beams 12, made fast to each other at their adjacent ends and to the junctions of the beams 9 and 19, with the beams 10 and 20. The various beams can be joined by welding. The planes of both upper and under faces of the boom extend upward and outward from the dock or pier and converge; and the outer beams 9 and 19 meet in a point at the free extremity of the boom and are permanently secured there to one another by welding or other means.

15 At the opposite extremity of the boom, the beams 9 and 19 are spaced apart, and are rigidly united at separated points to a length of vertical pipe 13, which extends below the boom and into a larger pipe 14 affixed in vertical position to the pier along the corner thereof. At its 20 upper end the pipe 13 is received in a bearing at the outer end of a bracket 15, affixed to the pier and projecting out from the corner of the deck 1. The pipe 13 thus serves as a journal or swivel, so that the boom can turn in the bracket 15 and the tubular bearing 14. The pipe 14 runs through the platform 3 and the bottom of the pipe 14 is fixed to the pier by metal retainer 16, at its lower end. Within the pipe 14 is counterweight 18, which cooperates with the landing gear in a manner shortly to be explained.

Welded or otherwise attached to the junctions of the beams 20 and the outer beams 19 on both sides of the boom 8, are beams or braces 21 extending downward and inclined towards the tubular bearing 14. They are made fast at their lower ends to beams 22 at both sides of the boom; the beams 22 being substantially vertical and secured to the junctions of the beams 10 and 20 with the inner beams 9 and 19 respectively. The tops of the beams 21 and 22 at their junctions with the boom 8 are connected by braces 23, and the ends of the braces 23 are joined at both sides of the boom to the junctions of the beams 20 and outer beams 19 and the beams 10 and inner beams 9. A third brace 24 at each side of the boom is made fast to the middle of each beam 21, the junctions of the beams 20 and inner beams 19 and the inner beams 9 and journal 13. Each pair of beams 21 and 22 meet at approximately the level of the platform 3, and their united ends are shaped to present bearings for a shaft 25 extending across the adjacent end of the gangway member 7. The ends of the shaft 25 are engaged by said bearings, and each pair of beams 21 and 22, with the braces mentioned, thus constitutes a rigid depending framework or truss supporting one end of the landing gear and pivotally connected to same. The beams and the trusses are further strengthened by short bars 26 uniting the junctions of the beams 10 and outer beams 9 to the junctions of the beams 21, beams 20 and outer beams 19, at each side.

The counterweight 18 is affixed to one end of a wire rope or chain 27 which passes up out of the top of the pipe 13 and over pulleys 28 on the inner and outer ends of the boom 8. The lower end of the pipe is closed by a cover 29. Below the free extremity of the boom, the upper end of the rope is made fast to the middle of a cross bar or pipe yoke 30. Between the element 30 and the outer pulley 28 I may affix an eyelet 31 to the boom to prevent the displacement of the rope from the pulley. Both ends of the element 30 are connected by thinner ropes or cables 32 to the landing gear at the junction of the stair member 6 and the gangway member 7.

These members are united at their adjacent ends by a universal joint illustrated in Figures 3 and 4. This joint comprises a transverse shaft 33, which extends through openings in the adjacent ends of the side beams 34 of the gangway member 7. Similar bearing openings are in the longitudinal side beams 34 at the opposite ends for the shaft 25. At the center of the shaft 33 is a horizontal journal 35, projecting forward and having at its rear end an extension 36 with a bearing opening through which the shaft 33 passes. The journal 35 has a projection on its front end with threads to receive a lock nut 37. This nut retains the journal, in a bearing 38, carried by a vertical web 39 that is part of the structure of the stair member 6. A washer 40 is interposed between the nut 37 and the bearing 38 and overlaps the adjacent end of the bearing 38. The web or plate 39 is strengthened and reinforced by an extension 41 united thereto at the rear of one of the steps at both sides of the stair member; and the shaft 33 also carries on each end an antifriction roller 42 which makes contact with the web 39 and eliminates friction. The extension 36 has a screw 43 that enters a groove or keyway 44 in the shaft 33 and keeps the journal at the middle point thereof.

The side beams of the stair member are shown 75

at 45, and the web 39 extends across from one to the other. The steps between the side beams are indicated at 46; and the upper step is extended back and is united along its lower face to the transverse vertical web 39. It also carries along its rear edge a fixed depending metal plate 46' which screens the shaft 33, this shaft lying between the plates 39 and 46'; and the side beams 34 of the gangway member project far enough out from the floor 48 of the gangway member for this purpose. The floor 48 has transverse cleats 49 to prevent users from slipping. On the outer ends of the shaft 33, beyond the side beams 34 of the gangway member 7 are bearings 50 for the shaft 33, and these bearings have perforated lugs 51 to which are attached U-shaped links 52 which connect this shaft to the ropes 32.

Whenever a vessel arrives at the pier, the boom is swung to bring the landing gear above its deck; the shaft or column 13 rotating in the bearing 14, and the gear being held raised by the weight 18. The stair member 6 can then be seized by a crewman and pulled down till the stair member rests on the deck 5 of the ship. The landing gear swings on the shaft 25, and the stair member 6 rises and falls as the boat is rocked by the waves; and the two members 6 and 7 swing sideways together if the boat swings.

The underside of the stairway member 6 has a frame abutment at each side made of braces 53 and 54 joined at their outer ends and adapted to engage stops 55 on the bottom of the gangway member 7. The outer or lower end of the stair member is chained to the deck of the vessel as shown at 58. The rise and fall of the vessel thus merely bends the landing gear, which yields at the shaft 33; and if the vessel drops into a trough between waves, the gear is pulled down to the lower position indicated in Figure 2.

The stops 54 and 55 may be cushioned. The whole landing gear is normally held up by the weight 18 and the stops 54 and 55 support the member 6 in an inclined position, so that it will not swing loosely when there is no boat under it. Hence it can be more easily reached and pulled down to be made fast by the chains 58. A lift of the vessel on the crest of a wave will lift the landing gear and lower the weight 18. The landing gear is thus always operated as required and can be used whether the water is calm or rough.

The landing gear has hand rails 57, and the vessel is moored to the ring 17 by the line 58. The rails 57 are on the gangway member 6 and the rails 47 are on the stairway member 7.

The steps of the stairs are always virtually horizontal, while the vessel 5 moves up and down with the waves through a distance of several feet, and sideways as much as four feet. The landing gear enables a person to walk from the vessel up the stair member 6 and over the gangway 7 to the pier, even when high winds prevail. The wharf or pier carries suitable supports 59 to bear the weight of the platform 3.

Having described my invention, what I believe to be new is:

1. Landing gear comprising a gangway member, a stair member, a universal joint connecting the stairway member to one end of the gangway member, a boom mounted to swing from side to side, frame means depending from said boom, the opposite end of the gangway member being pivotally attached to said frame means, and means for yieldably connecting the jointed ends of said members to said boom.

2. Landing gear comprising a gangway mem-

ber, a stair member, a universal joint connecting the stair member to one end of the gangway member, a boom mounted to swing from side to side, frame means depending from said boom, the opposite end of said gangway member being pivotally attached to said frame means to be movable about a horizontal pivot, and means for yieldably uniting the jointed ends of said members to said boom.

3. Landing gear comprising a gangway member, a stair member, a flexible connection between said stair member to one end of the gangway member, a boom mounted to swing from side to side and bearing truss frames extending downward, a horizontal shaft carried by said frames, the opposite end of the gangway member pivotally engaging said shaft, and means for yieldably suspending said flexible connection from said boom, said means including a cable on said boom, united to said flexible connection, and a counter-weight made fast to the opposite end of said cable.

4. Landing gear comprising a boom having upper and lower beams, a column affixed to said boom at one end, said upper and lower beams converging towards the opposite end, truss frames extending downward carried by said boom, a transverse shaft carried by said frames, a gangway member having one end pivotally engaging said shaft, a stair member, means connecting said stair member to the other end of the gangway member, means for yieldably attaching said first named means to said boom, and an upright tubular bearing in which said column is rotatably mounted, said means connecting said members including a universal joint between said members.

5. Landing gear comprising a boom having upper and lower beams, a column affixed to said boom at one end, said upper and lower beams converging towards the opposite end, truss frames extending downward carried by said boom, a transverse shaft carried by said frames, a gangway member having one end pivotally engaging said shaft, a stair member, means connecting said stair member to the other end of the gangway member, means for yieldably attaching said first named means to said boom, and an upright tubular bearing in which said column is rotatably mounted, said means connecting said members including a shaft at the other end of the gangway member, a journal rotatably mounted on the last-named shaft, and a bearing on the stair member engaging said journal.

6. Landing gear comprising a boom mounted to swing from side to side, struts depending from said boom, a gangway member having one end pivotally supported by said struts, a stair member, means for connecting the opposite end of the gangway member to the stair member and means for yieldably suspending said members at

their connected ends from said boom, said connecting means including a universal joint between said members.

5 7. Landing gear comprising a boom mounted on a dock to swing from side to side, struts depending from said boom, a gangway member having one end pivotally supported by said struts, a stair member, flexible means for connecting the opposite end of the gangway member to the stair member and means for yieldably suspending said members at their connected ends from said boom, said suspending means including a cable united at one end to said members, guide wheels on the boom for the cable, and a counter-weight to which the cable is fastened at the opposite end.

10 8. Landing gear comprising a boom mounted to swing from side to side, struts depending from said boom, a gangway member having one end pivotally supported by said struts, a stair member, means for connecting the opposite end of the gangway member to the stair member and means for yieldably suspending said members at their connected ends from said boom, said connecting means including a universal joint between said members, said suspending means including a cable united to said members, guide wheels on the boom for the cable, and a counter-weight to which the cable is fastened.
